UNITED STATES PATENT OFFICE.

SAMUEL EARL MOSHER, OF CHILlicothe, OHIO.

ELECTRIC LIGHTING DEVICE.

SPECIFICATION forming part of Letters Patent No. 625,786, dated May 30, 1899.

Application filed February 28, 1898. Serial No. 671,968. (No model.)

To all whom it may concern:

Be it known that I, SAMUEL EARL MOSHER, of Chillicothe, in the county of Ross and State of Ohio, have invented certain new and useful Improvements in Electric Lighting Devices; and I do hereby declare the following to be a full, clear, and exact description of the invention, such as will enable others skilled in the art to which it pertains to make and use it, reference being had to the accompanying drawings, which form part of this specification.

My invention relates to improvements in electric lighting devices, and pertains to a device adapted to light at the top or within the top of a chimney.

The object of my invention is to provide an electric lighting device especially adapted for use in connection with the incandescent gas-burners such as the Welsbach, Niagara, Apollo, and others, the device being constructed and arranged to move over, within, and without the upper end of the chimney and producing a spark at the top or within the top of the chimney for lighting the burner.

In the accompanying drawings, Figure 1 is a perspective view of my invention shown attached to an incandescent gas-burner and in position for operation. Fig. 2 is an enlarged side elevation of the sparking devices looking from one side thereof, and Fig. 3 is a similar view looking from the opposite side thereof. Fig. 4 is a detached view of the pulley or sheave which carries one of the sparking-arms. Fig. 5 is a view of the arm which carries the other sparking members. Fig. 6 is a sectional view taken longitudinal the spindle or shaft of the sparking members, showing the parts in position thereon.

A indicates an incandescent gas-burner to which my invention is applied.

B is a horizontal arm constructed to be attached to the lower portion of the burner, as illustrated, and is here shown of a hollow form and adapted to receive the lower laterally-bent end D of a standard E. The arm B may be constructed to be horizontally adjusted, if desired, and the standard E, projecting upward parallel the chimney of the burner, may also be longitudinally adjustable for the purpose of fitting the device to burners having chimneys of different types. The standard E, I preferably form of a tube,

through which the wire connections and the operating chain or cord, as hereinafter described, may pass, though the standard may be made solid and the wires on the outside thereof without departing from the spirit or scope of my invention. A screw or other clamping device F is provided for holding the lower end of the standard E in the arms B, as clearly shown. The upper end of the standard is provided with a laterally-projecting spindle or shaft G, upon which is journaled a sheave or pulley H. A spiral spring I is wrapped around this spindle and has one end connected with the sheave or pulley and its opposite end connected in any manner with the journal or shaft. Connected with this sheave is a curved sparking member or arm J, preferably formed of wire, and the said spiral spring normally holds the arm backward, as illustrated in solid lines in Fig. 1. Situated also upon this journal is a plate or arm K between the inner side of the sheave or pulley and the standard. A coiled spring L has one end connected with this plate and its opposite end connected with the sheave or pulley and the said spring normally holding the plate backward, as shown in solid lines in Fig. 1. This plate is provided with a socket M, carrying an insulating material N, and placed within this insulating material N is a sparking member or arm P. It will thus be seen that two sparking members or arms are provided, and they are curved, as here shown, so that when they are thrown forward, as shown in dotted lines in Fig. 1, they will move within the upper end of the chimney, as shown. The spring connecting the plate and the sheave unites the sheave and the plate, as will be understood, and when the sheave is rotated to move its sparking member or arm within the chimney it carries with it the plate which has the other and coacting sparking member or arm. A cord, wire, or chain is connected with the tube, and when the standard E is of tubular form, as here shown, the chain, wire, or cord passes down through the tube and is provided at its lower end with a ball, by means of which it can be readily drawn downward. The plate is provided with an inwardly-projecting arm Q, which engages the standard and limits the backward movement of the plate. The plate

is provided with a slot R and the sheave with a projecting arm or pin S, extending into this slot, and the independent movement of the sheave and the plate is limited by this slot. 5 The upper end of the standard is provided with a projecting arm a and the plate with a coacting projecting arm b, so that when the plate through the medium of the sheave is carried forward it is limited in its movement 10 by the engagement of these arms. The operation of these members is as follows: A downward pull on the chain or cord revolves the sheave and throws its sparking member or arm forward, and as the sheave is connected 15 with the plate through the medium of the spring the plate is carried forward until it is stopped by the engagement of the arm with the standard or the projection, and a continued pull upon the chain moves the sheave independent 20 of the plate, which has been stopped, thus moving the sparking-arm of the sheave farther forward or farther within the chimney than its coacting sparking member of the plate. The sheave sparking member may 25 be provided at its end with a fine spring, which may be formed of platinum wire, with one or more projecting ends c. These ends project, and when the sparking-arm of the sheave is moved forward after the plate has 30 been stopped the arms of this spring or the ends of fingers or arm engage the sparking member of the plate, and the further movement of the sparking member of the sheave causes the spring to disengage, and in this 35 way the spark is produced. The backward movement of the parts bring them to the relative position shown in full lines in Fig. 1 ready for a second operation. Passing also through the tubular standard E, when a tube 40 is used, are one or two wires which are connected in the circuit, and one of the wires has its end projecting, as shown at d, and the sparking member of the plate has a projecting end e, so that when the plate is moved forward 45 these two members will engage and make the electrical contact ready for the sparking through the medium of the coacting arm of the sheave and the spring. The other wire is connected with the upper end of the 50 standard in any suitable manner, and as the sheave is electrically insulated from the standard the wire is thus electrically connected with the sparking member of the sheave, though this connection may be made in any 55 other desired way. The projecting end of one of the wires which coacts with the projection of the sparking member of the plate may serve alone as the means for stopping the movement of the plate, though I prefer 60 to use the arms, as before described, which will be more permanent and not so likely to be bent out of position, and thus effect the relative position of the parts of the sparking mechanism. 65 From the above description it will be seen that a downward pull upon the wire or chain carries both of the sparking members together

over or within the upper end of the burner-chimney and that a continued pull moves the sparking member of the sheave farther and causes it or the sparking-spring before described in and out of contact with the sparking member of the plate, thus making and breaking the circuit and causing a spark. By the use of two arms, as here shown, carried by the sparking member of the sheave one or more sparks are produced at each operation of the device, which make the lighting more certain. If the engagement of these spring-arms is light with the coacting sparking member of the plate, then one or more sparks will be produced by the continued movement of the sparking member of the sheave and one or more sparks made when the sheave is being released and moves backward independent of the plate by the engagement of these spring-arms with the sparking member of the plate as the cord is being released. In this way one or more sparks are produced when the string is pulled. A device of this character which moves over or within the chimney is especially adapted for the Welsbach and similar incandescent lights. Where these lights are situated at an elevated point, as is usually the case, it is difficult to get 95 at them to light with a match without standing on a chair or other elevated support or to use a taper on the end of a rod. By means of my device it can be attached to the ordinary burner without any change whatever in 100 the burner and is adapted to move within and without the chimney and cause a spark at the right place for igniting the combined gas and air therein.

I do not limit myself to any detail of construction here shown, for this may be varied without departing from the spirit or scope of my invention, the essential feature of which is the moving of the sparking members over or within the chimney and causing a spark for the purpose of lighting the burner. Many changes and variations whereby this may be accomplished will readily occur to mechanics skilled in this line, and therefore I do not limit myself to the specific construction herein shown for effecting the desired result.

Having thus described my invention, what I claim, and desire to secure by Letters Patent, is—

1. The combination with a burner having a 120 chimney, of curved sparking members pivotally supported adjacent the upper end of the chimney and movable over and within the chimney and one independent of the other for causing a spark, substantially as described.

2. A sparking device comprising a standard, two sparking members movably connected with the standard, one of the sparking members movable independent of the other and yieldingly connected therewith, and means for moving one of the members, substantially as described.

3. A sparking device comprising two pivoted sparking members, one yieldingly con-

5 nected with the other, and movable independent thereof, and means for moving the independently-moving member thereby moving both members and one independent of the other for the purpose described.

10 4. The combination with a burner having a chimney of a standard supported at its lower end outside of the chimney extending parallel therewith and having its upper end adjacent the upper end of the chimney, two sparking-arms movably connected to the upper end of the standard, and means constructed and arranged to move the sparking members over the chimney and one independent of the other for causing a spark, substantially as described.

15 5. The combination with a burner having a chimney, a supporting-arm adjacent the upper end of the chimney, sparking members pivotedly connected with the supporting member upon an axis at right angles to the axis of the chimney and at a point between parallel tangential lines drawn to said chimney, whereby the contacts are movable over the 20 said chimney, substantially as described.

25 6. A sparking device comprising a support, a shaft or journal carried by the support, a pivoted sparking member upon the shaft, a spring connecting the shaft and the sparking member for holding it normally in one position, a coacting sparking member pivoted adjacent the first sparking member, a spring connecting the two members, a stop for the last said sparking member, a limiting means 30 between the sparking members.

35 7. A sparking device comprising a standard having at its upper end a shaft or jour-

nal, a sheave upon the shaft, a sparking member carried by the sheave, and a spring connecting the shaft and the sheave, a pivoted 40 plate, a spring connecting the sheave and the plate, one of the members having a stop and the other a projection, the plate provided with a stop for limiting its movement, the plate provided with a coacting sparking member, 45 and means for rotating the sheave whereby the members are moved together for a predetermined distance and then one independent of the other for causing a spark, substantially as described. 50

8. A sparking device comprising a support, two pivoted sparking members, one of the sparking members being yieldingly connected with the support, the other sparking member yieldingly connected with the first said sparking member, the sparking members having respectively a slot and a projection for limiting their independent movements, one of the sparking members having electrical contact with the standard, the other sparking member insulated therefrom, one pole of the battery connected with the standard or non-insulated sparking member, the other pole of the battery connected with a projection, and the insulating sparking member having a projection adapted to engage said projection when the sparking members are moved, substantially as described. 55 60 65

In testimony whereof I affix my signature in presence of two witnesses.
